Attorney

UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed March 16, 1922. Serial No. 544,168.

To all whom it may concern:

Be it known that I, WILLIAM F. HELMOND, a citizen of the United States, residing in Hartford, in the county of Hartford and 5 State of Connecticut, have invented certain new and useful Improvements in Typewriting Machines, of which the following is a specification.

The present invention relates to paper-fingers for typewriting machines, that is to say, to fingers which guide the paper partly around the platen and which carry rolls for holding the paper against the platen. More particularly, the invention relates to 10 paper-fingers, of this class, for guiding the paper across the printing line, and for holding the paper to the platen beyond the printing line by means of the rolls carried thereby; such fingers being usually adjustable 15 lengthwise of the platen according to the width of the paper, card or envelope to be held thereby.

For easy insertion and feed of the paper, the rolls should have considerable resiliency; and, by having the sheet-metal of the fingers light enough, such delicacy of action of the rolls may temporarily be obtained. If, however, the fingers are made thin enough to provide such resiliency, they 20 are easily bent and distorted, with the result that the rolls may bear unequally, unevenly, or not at all, on the paper. If, on the other hand, fingers which thus directly carry the rolls be made heavy enough to 25 stand wear and tear without injury, then the rolls may lack the desired delicacy of action.

A feature of the present invention is the provision of means whereby the rolls may 30 have a play to and from the platen independently of, or with respect to, the fingers; so that the rolls may have the desired resiliency and certainty of action regardless of stiffness, or even of injury, of the fingers; 35 and vice versa, so that the fingers may be of any required strength without regard to the resiliency required by the rolls.

In attaining the above-mentioned object, in the preferred form of the invention, the 40 rolls, instead of having their bearings directly on fingers of delicate spring sheet-metal, are supported on spring metal plates of the required lightness and resiliency,

which plates in turn are superimposed on stiffer sheet-metal fingers having openings 55 therein through which the rolls engage the platen.

Another feature of the invention is the provision of means for quickly, accurately, and detachably securing the roll-carrying plate to the finger, and for securing both of these parts to their supporting bracket; not only for purposes of assembly, but so that an injured or worn finger or roll may be replaced without discarding the other of such 65 parts.

A further feature of the invention is a construction of paper-finger-supporting bracket such that the bracket, though made of comparatively light sheet-metal, 70 will not, by bending, bind on its rail when pressure is applied to slide the finger lengthwise of the platen.

Other features and advantages will hereinafter appear.

In the accompanying drawings,

Figure 1 is a view, in side elevation, cross-sectional through the platen on the line 1—1 of Figure 2, of the platen-frame and paper-finger mounted thereon, and certain associated parts.

Figure 2 is a front view of the assembly shown in Figure 1.

Figure 3 is a detail view, in perspective, of the bracket which carries the paper-finger, and of a part of the rod on which the bracket slides.

Figure 4 is a view, in perspective, of the paper-finger; the feed-roll being disconnected therefrom.

Figure 5 is a perspective view of the feed-roll of the paper-finger, and of the device for supporting the same on the paper-finger.

Referring to the drawings, the platen-frame consists of side pieces 10, one only of which is shown, connected by rods 11 and 12, and having revolvably mounted thereon a platen 13. The usual lower rear and front feed-rolls 14 and 15, respectively, are indicated in dotted lines in Figure 1. As indicated by the type-bar 16, shown in dotted lines in Figure 1, the machine is a front-strike machine. In fact, the mechanism thus far described is that found on the Underwood standard typewriting machine.

The paper-fingers, only one of which is shown in the drawings, are carried by arms or brackets 17, supported on the rod 11. In Figure 1, the bracket 17 is shown in the 5 position in which it holds the paper-finger in operative, paper-engaging position. The paper-fingers are, however, adapted to be thrown upward, and away from the platen, to an inoperative position, and, for this purpose, the arms or brackets 17 are pivotally connected to the rod 11. For holding the brackets 17 in effective position, the rod 11 is splined at 18, and a lateral shelf or extension 19 carries a leaf-spring 19^a, which, 10 in turn, carries a key, indicated at 20 in Figure 1, for engagement with the spline in the rod 11. When the bracket is turned to the Figure 1 position, the key 20 registers with the spline 18, and the leaf-spring 19^a causes the key to enter the spline and lock the bracket in its normal position. When 15 the arm or bracket 17 is thrown up, to remove the paper-fingers from the platen, the leaf-spring, referred to, permits the key 20 to be forced out of the spline-way 18, but causes the key thereafter to bear upon the rod 11 in such manner as to hold the bracket in upper position against accidental displacement. For throwing the bracket up and 20 down with the paper-finger, the bracket has at its forward end a finger-piece 21. The connections of the bracket 17 to the rod 11, just described, are those found on the Underwood standard typewriting machine, and 25 so are not more specifically illustrated.

As a part of the present invention, however, the bracket-arms 17 have offset ribs or flanges 22, 23 thereon, which are continued around to form offsets or flanges on the 30 proximate ends of the shelf-portions 19; thus re-enforcing the arms 17 against lateral spring and making their connections to the shelf-portions 19 more rigid. This rigidity of the bracket as a whole and the elimination 35 of spring in the arm 17 is highly desirable, because the brackets are to be slid with the paper-fingers to any desired marginal position on the rod 11; and, if the arms 17 are readily sprung laterally, they will bind upon the rod 11 and interfere with prompt and easy longitudinal adjustment of the paper-fingers on the rod 11.

For supporting the paper-finger on the bracket, the latter, at its forward end, has 40 a laterally-offset arm or plate 24, provided with screw-holes 25. The paper-finger 26 is curved in general conformity to the curvature of the platen, but, at its upper end, has a flat offset portion 27 which is adapted to 45 be set against the back of the bracket-plate 24, and, at its upper end, is curved forward at 28, to overlie the top edge of the bracket-plate 24. The paper-finger also has two screw-holes 29 adapted to register with the 50 screw-holes 25 in the plate 24. The paper-

finger is held to the bracket-plate 24 by means of screws 30 (see Figure 1), which pass through the screw-holes 29 in the paper-finger and through the screw-holes 25 in the plate 24, and which thread into a block or 55 plate 31 behind the paper-finger.

As shown in Figure 4, the paper-finger has a transverse opening 32 therein, through which the roll 33 may engage the platen or the paper thereon. Ears 34 in the paper-finger connect and unify the parts of the paper-finger forward and rearward of the opening 32 therein. The roll 33 does not have its bearings directly in the paper-finger, but is carried by a pin 35 which bears in ears 36, struck upward from and forming part of a thin, resilient piece of sheet-metal 37. The roll-carrying piece or arm 37 is offset at 38, at its upper end, and in the offset 38 are screw-holes 39 of the same size and 60 spacing as the screw-holes 29 in the finger-piece 26. As shown in Figure 1, the roll-supporting arm 37 is set on the finger-piece 26 in such manner that the roll and its supporting ears 36 lie between the ears 34 of the paper-finger, with the roll itself in registration with the opening 32 through the paper-finger. When in this position, the screw-holes 39 register with the screw-holes 29, so that, as shown in Figure 1, the screws 30 65 which hold the paper-finger to the bracket 17 also hold the roll-carrying arm 37 in place. It will be noted that the offset 38 of the roll-carrying arm lies between the paper-finger and the bracket-plate 24 when the parts are 70 assembled.

As shown in the drawings, the paper-finger 26 is of heavier or thicker sheet-material than the roll-carrying arm 37. The thickness of the roll-carrying arm 37 and 75 the spring set of the same is such as to result in a delicate spring action of the roll on the platen or paper; whereas the thicker stock of the finger 26 gives the latter all the 80 strength and rigidity which its several functions require.

It will be noted that, since the roll-carrying piece 37 is separable from the finger-piece 26, an injured finger-piece or a 85 worn or twisted roller may be removed and another substituted therefor without discarding the uninjured part. It will also be seen that the offset 28 on the finger-piece 90 may serve as a means for effecting a preliminary and approximately correct positioning of the roll-bearing plate on the finger-piece; and that, with these parts thus positioned, one on the other, the offset 28 on the finger-piece is hooked over the bracket-arm 24 and serves as a means for approximately positioning the parts on the bracket 95 for insertion of the screws.

Variations may be resorted to within the scope of the invention, and portions of the 100 improvements may be used without others.

Having thus described my invention, I claim:

1. In a typewriting machine, a revolute platen, a relatively stiff sheet-metal finger 5 for guiding the paper around the platen, a relatively resilient sheet-metal plate, a paper-holding roll carried by said plate for yieldable engagement with the platen independently of the finger, and a bracket 10 on which the finger and roll-holding plate are held, the plate on top of the finger, with the roll engageable with the platen through an opening in the finger.

2. In a typewriting machine, a revolute 15 platen, a relatively stiff sheet-metal finger for guiding the paper around the platen, a relatively resilient sheet-metal plate, a paper-holding roll carried by said plate for yieldable engagement with the platen independently of the finger, and a bracket on 20 which the finger and roll-holding plate are held, by one end of each.

3. In a typewriting machine, a revolute platen, a finger for guiding and holding the 25 paper on the platen, a sheet-metal bracket for supporting the paper-finger, and a rod along which the bracket is adjustable lengthwise of the platen; the bracket comprising an arm extending lengthwise of the rod 30 with ears or lugs spaced apart thereon for engagement with the rod, and an arm projecting at an angle therefrom, for sliding the bracket, the edges of the bracket being offset across the junction of said arms

thereof to stiffen the same against any angular movement which would tend to cause the bracket to bind on the rod. 35

4. In a typewriting machine, a revolute platen, a relatively stiff long finger for 40 guiding the paper around the platen, and a relatively resilient short plate having one end detachably connected to one end of the finger, and having a paper-holding roll mounted on the free end thereof; said plate and roll normally positioned to yieldingly 45 hold the paper to the platen independently of the finger.

5. In a mounting for a paper-guiding finger for a revolute platen, the combination of a bracket for supporting the finger, 50 and a rod extending lengthwise of the platen, along which the bracket is slidable; said bracket comprising a member extending lengthwise of the rod, lugs spaced apart thereon, and an arm, a portion of which 55 forms one of said lugs, projecting at an angle from said member; the edges of the bracket adjoining the angular junction of said member and said arm being bent to form continuous flanges to stiffen the same 60 against lateral spring, to prevent the bracket from binding upon the rod when pressure is applied to said arm to slide the bracket along the rod.

WILLIAM F. HELMOND.
